UNITED STATES PATENT OFFICE.

FRANK C. AXTELL, OF SOUTH PASADENA, CALIFORNIA, ASSIGNOR TO AXTELL RESEARCH LABORATORIES, INC., OF LOS ANGELES, CALIFORNIA, A CORPORATION OF CALIFORNIA.

PETROLEUM-REFINING PROCESS AND REAGENT FOR THE REMOVAL OF SULPHUR.

No Drawing. Application filed December 27, 1926. Serial No. 157,427.

My present invention relates to the production of refined hydrocarbon products, (e. g., gasoline, kerosene and lubricating oil, or other desired fractions) by steps which 5 include a novel acid treatment, optionally followed by a distillation.

It is well known that such crude oils as have a considerable sulphur content in their natural state ordinarily produce distillates 10 having a correspondingly high sulphur content; and that such sulphur has been removed only at considerable expense, to comply with commercial requirements.

It is also well known that sulphuric acid 15 has a separating action upon the sulphur compounds in these distillates,—tending to combine therewith and/or to separate them from the oils; but, as is also well known, the action of the sulphuric acid may also be 20 exerted upon various desired hydrocarbon constituents of the distillates (such as the unsaturated and aromatic hydrocarbons that may be present)—causing polymerization, oxidation and/or sulphonation of these or 25 other valuable constituents of the oil, which have thus been incidentally deposited and drawn off, with the sludge, in such percentages as to involve a loss that is extremely serious both to the refiner and to the public 30 and to the best of my knowledge, there is—at the present time—no method whereby the action of the sulphuric acid may be “controlled” to the point of removing undesirable constituents and leaving the desirable constituents, the exercise of the control varying 35 with the quality of the oil.

Most petroleum distillates obtained from western oils contain considerable quantities of unsaturated and/or aromatic hydrocarbons,—this being particularly true of distillates and residuals from asphaltic base oils, from shale oils and/or from cracked oils. Such distillates may contain from 20% to 50% of unsaturated hydrocarbons,— 40 which possess great energy value but which tend to go into any ordinary sulphuric acid sludge, as heretofore produced.

Sulphuric acid, as used in quantities and strength required to reduce the amount of sulphur in hydrocarbons to a permissible 45 quantity, has carried with it, into the acid sludge, from 5% to 25% of the original

volume of the oil subjected to treatment. For example, in the treating of cracked distillates (in which the sulphur compounds are generally very resistant to acid treatment) it has been common to use a relatively large amount of highly concentrated sulphuric acid, in order to secure a fuel with a relatively low percentage of sulphur and to conform with commercial specifications; the refining loss, due to the mentioned polymerization, sulphonation and oxidation effects of sulphuric acid upon unsaturated hydrocarbons and/or aromatic hydrocarbons, has accordingly been very great; and its seriousness can be appreciated only when it is realized that the action referred to tends to eliminate from the distillates some of those constituents which are of greatest value and 55 which tend to an anti-knocking effect,—comparable with that obtained (at considerable expense and not without hazard) by the use of tetra-ethyl lead.

Now, I have discovered that the polymerizing, oxidizing and sulphonating powers or actions of sulphuric acid can be very favorably modified by the addition thereto of a substance or substances capable of reacting therewith and/or overcoming (by nonaqueous dilution, or by consuming or reducing or inhibiting the same) its capacity for polymerization; I find that these desired effects can be obtained without adversely affecting its affinity for sulphur compounds; and I 60 also find that, when my preferred “satisfied” acid reagent is mixed with hydrocarbons to be refined, it appears content to combine with the sulphur-containing and nitrogenous compounds therein,—forming a sludge, of 65 low hydrocarbon content, which is capable of being quickly separated as a mixture of so-called “sulphur oils” containing acid.

More specifically, I have discovered that if fuming sulphuric acid (preferably containing a considerable percentage of SO_3) be admixed and/or agitated (as may be done at an ordinary temperature) with an excess quantity of an aromatic hydrocarbon such as 70 commercial benzene, toluene or xylene, or a mixture of these (the mentioned excess being such that, after agitation of the mixture, a 75 layer of the aromatic hydrocarbon or hydrocarbon mixture separates and rises, to consti-

tute an upper stratum,—leaving a lower stratum of acid saturated with aromatic hydrocarbons and/or products arising from the reaction of sulphuric acid and/or sulphuric anhydride therewith) there results an acid reagent which has but little affinity even for those petroleum hydrocarbons that are capable of polymerization and which has practically no power of oxidation and/or sulphonation of unsaturated or other desired hydrocarbons.

I have also discovered that, upon treating hydrocarbon distillates with an acid reagent derived substantially as above indicated, 15 and thereby apparently satisfied as to its polymerizing, oxidizing and sulphonating qualities, the sulphur compounds in any such hydrocarbon distillate (or in any other sulphur-containing material treated in the 20 manner referred to) are so combined either with the sulphuric acid or with the sulphuric anhydride, or with aromatic derivatives produced thereby, as to form a fluent acid sludge, having comparatively small 25 volume, which is readily separable from the hydrocarbons; and I have discovered also that such portion of the sulphur content of the treated distillate or other material as remains in the oil is likely to have undergone 30 transformation into comparatively complex sulphur compounds,—these being ordinarily of such high boiling points that, upon a subsequent distillation, they tend to remain very largely in the still bottoms, after commercial gasoline and/or any other desired 35 products are driven off by the distillation,—economically producing a substantially white and sweet gasoline of very low sulphur content, or other products of corresponding purity.

As is known, various aromatic hydrocarbons such as benzene, toluene and xylene dissolve in highly concentrated or fuming sulphuric acid without undergoing appreciable polymerization or oxidation. The products thus obtained, including those which result from so-called side-reactions, are not single definite chemical compounds,—being mixtures of certain aromatic sulpho acid 45 compounds, and other products of reaction, with free sulphuric acid and/or sulphuric anhydride. Accordingly, while the acid mixtures referred to must contain certain known or unknown sulpho acids, it is not 50 my purpose separately to use any single definite compound, as the use thereof would be unduly expensive and also apparently less effective, for my indicated purpose, than the use of the reagent mixtures herein described.

The exact proportions of the ingredients of my reagent mixtures may vary. I find, for instance, that if fuming sulphuric acid be treated at ordinary temperatures with an 55 excess of commercial benzene, toluene or

xylene, or with mixtures of the above (preferably in such proportions that, after agitation, an excess of the hydrocarbon or hydrocarbons separates,—rising to the surface of the mixture and so leaving the combined acid mixtures) the resultant mixture or reagent may be used either by itself or blended with a further quantity of sulphuric acid; and that it, in either case, forms an excellent reagent for use upon petroleum oils and distillates for the removal of sulphur and objectionable compounds; and I emphasize that by the use of various blends of my reagent with further quantities of sulphuric acid (depending upon the quality of the treated oil), the polymerizing, oxidizing and sulphonating properties of sulphuric acid on the unsaturated and other hydrocarbons in the treated oil can be either entirely obviated or satisfactorily controlled,—so that, when such petroleum or other distillates are treated as hereinafter described, the refining losses may be reduced to a minimum.

By procedures of the general character referred to, the operator is enabled to use even a relatively large proportion of the mentioned reagent mixture to the oil treated, without suffering those heavy refining losses which have been referred to as incidental to the separate use of sulphuric acid. The foregoing constitutes a peculiarly valuable treatment in the case of cracked distillates, in that the proportion of sulphur compounds therein is high and in that the sulphur compounds in such distillates are commonly of such great stability as to resist treatment with small quantities of ordinary sulphuric acid.

Referring further to the special advantages obtainable from the use of my reagent and process upon cracked distillates, when a distillate containing a relatively high percentage of sulphur compounds is treated with my new reagent, a large proportion of such sulphur compounds combines directly with the aromatic acid reagent, remaining dissolved therein or combined therewith. Upon separation of the acid sludge from the oil, a part of the sulphur content of the sludge may be separated directly by diluting the latter with water; but another portion of the sulphur content of the original distillate is evidently acted upon chemically by the reagent, with production of complex sulphur compounds of very high boiling-point. Although a portion of the latter may remain dissolved in the oil, most of this portion may be economically separated by mere retention in the still, upon a subsequent distillation as hereinafter described.

In view of the foregoing, it will be understood to be a general object of my invention to provide a process for the treatment of hydrocarbon distillates, or the like,

whereby deleterious compounds may be cheaply and expeditiously removed without adversely affecting the valuable unsaturated and other especially valuable hydrocarbons ⁵ therein contained.

Otherwise stated, it is an object of my present invention to provide a cheap and effective reagent and process whereby hydrocarbon distillates may be treated, to remove deleterious compounds therefrom, without unavoidably polymerizing, oxidizing or sulphonating such distillates; and whereby refined distillates may be produced without undue collateral loss in volume, in fuel ¹⁰ value or in other desired properties, during or subsequent to such treatment.

It is a specific object of this invention to provide, for use in the separation of sulphur compounds from desired hydrocarbons, a reagent which includes sulphuric acid and/or sulphuric anhydride in admixture with a nonaqueous diluent,—such as an aromatic body or bodies, or derivatives produced by the action of sulphuric acid or sulphuric ²⁰ anhydride thereon.

A further object of my invention is to provide a reagent of the class described which is susceptible to the mixture therewith of sulphuric acid in the treatment of oils, ³⁰ whereby a definite control may be had in the desulphurizing and refining of the oils treated.

It is a further object of my invention to provide, for the use mentioned, a reagent ³⁵ containing one or more aromatic sulphonnic acids and/or derivatives thereof, these being preferably employed in the presence of sulphuric acid and/or sulphuric anhydride and in the substantial absence of water; and it is a specific object of this invention to utilize ⁴⁰ what I hereinafter refer to as a "sulphonnic-sulphuric" reagent mixture, of the general character indicated, in the commercial production of colorless and sweet gasolines, having high calorific value and unusual ⁴⁵ anti-knocking properties, or in the production of other hydrocarbon mixtures of corresponding merit,—according to the fraction or material treated and/or the products desired.

In applying my invention to the treatment of "cracked" petroleum distillates, for instance, I may proceed according to the following outline: (1) preparing the reagent by combining a nonaqueous sulphuric acid ⁵⁰ (preferably fuming) with commercial or other benzene, toluene and/or xylene; I may (2) treat the distillate by agitation or contact with a suitable quantity of this reagent, (3) allow the acid sludge to settle, and then ⁵⁵ (4) separate the treated distillate from the acid sludge. I may then (5) treat the distillate with a small quantity of a good basic clay, (6) separate the clay from the distillate ⁶⁰ by sedimentation or filtration, (7) agi-

tate the treated distillate with a small quantity of a strong solution of an alkali such as caustic soda, caustic potash, or a carbonate of sodium or potassium, (8) separate the distillate from the aqueous alkaline solution ⁷⁰ and (9) finally subject the oil so obtained to another distillation,—any sulphur which failed to enter the sludge then remaining mostly in the still bottoms.

As a specific illustration of the method ⁷⁵ employed and the results obtained, I may give the following: A given quantity of an "end-point gasoline" distillate produced by previous "cracking", said distillate having an end boiling-point of 437° F. and containing about 0.68 percent of sulphur, was treated with twenty-five pounds per barrel of my reagent, as made by chemically and physically saturating a fuming sulphuric acid with "benzene" at an ordinary temperature. ⁸⁰ Upon beginning the agitation of the treated oil-plus-reagent mixture, it assumed a milky appearance; and upon continued agitation it gradually cleared up, finally becoming perfectly transparent and of a very light ⁸⁵ yellow color,—an acid sludge settling, in small volume, to the bottom of the container. The oil was then separated from the acid sludge (the refining loss being about 2.56 percent by volume) and it was next treated with about four pounds per barrel of so-called Death Valley clay, being agitated for five minutes therewith, and then filtered,—the filtrate being practically colorless.

The filtered oil was then agitated with ⁹⁰ about three pounds per barrel of a 33 percent aqueous solution of sodium hydroxide, and was separated from the aqueous solution. At this point the oil was found to have a sulphur content of 0.30 percent.

The treated oil, hereinafter referred to as refined gasoline, was then blended with a kerosene distillate, so that the final blend contained fifteen per cent, by volume, of such kerosene distillate, the said kerosene distillate having a boiling range between 375° F. and 550° F. and containing 0.08 of sulphur. The blended distillate was then distilled with a small quantity of caustic potash solution, until the temperature at the dephlegmator ¹⁰⁰ head reached about 225° F. At this point steam was introduced into the still and the distillation continued until the original volume of the refined gasoline had passed over,—leaving the kerosene still-base in the still. The gasoline thus obtained, when separated from the condensed water and dried, showed a sulphur content of 0.11 per cent; whereas the kerosene still-base had a sulphur content of 1.0 per cent.

The acid sludge, which was so fluent as to necessitate no use of water in removing the same, when separated as above was diluted with water,—upon which the so-called "sulphur oil" separated and rose to the surface.

This oil was removed and washed and, upon analysis, was found to contain 6.44 per cent of sulphur and to have a specific gravity of 0.90. This is an unusually high sulphur content for such oils,—its character being apparently due to the fact that there occurred little or no polymerization of unsaturated hydrocarbons by the described acid treatment.

- 10 A gasoline distillate produced as described has a pure hydrocarbon odor, is practically colorless and it satisfies all the tests laid down in the various standard specifications,—in addition to which it contains practically the entire quantity of unsaturated hydrocarbons contained in the original distillate, and contributing to both the quality and quantity of the product.
- Further to illustrate the value of my reagent mixture in the treatment of a "cracked" gasoline, and the fact that the proportions of the ingredients of this mixture may vary, I next mention a case in which a portion of the sulphur compounds contained in a "cracked" distillate were extremely resistant to ordinary treatment (with plain sulphuric acid): A quantity of a "cracked" "end-point" gasoline distillate containing 0.79 per cent of sulphur and 22 per cent of unsaturates was agitated with twenty-five pounds per barrel of a reagent made by saturating a fuming sulphuric acid (containing about 20 per cent SO_3) with a commercial benzene. To this acid mixture there was then added fuming sulphuric acid in such amount that the actual reagent employed for treating the distillate consisted of $12\frac{1}{2}$ pounds per barrel of the hydrocarbon-saturated acid reagent and $12\frac{1}{2}$ pounds of fuming sulphuric acid containing 20 per cent SO_3 . The distillate was then agitated with this latter acid and reagent mixture and treated exactly as has been described in the previous illustration. After this treatment, and before a final distillation, the sulphur content was found to have been reduced to 0.26 per cent; and after distillation the unsaturates in the final distillate was 21.2 and the sulphur content 0.09 per cent. The refining loss in this case was 2.9 per cent after treatment with the aryl-acid reagent described.

In the foregoing, the inhibiting action of the aromatic hydrocarbons as regards the sulphonating, polymerizing and oxidizing action of sulphuric acid on "cracked" petroleum distillates is strongly exhibited; and it is shown to be unnecessary that the fuming sulphuric acid employed be entirely saturated with the aromatic hydrocarbons. However, I find that it is quite essential in the attainment of best results, to first prepare the reagent by completely saturating the acid with an aromatic hydrocarbon and then "diluting" this reagent with the further addition of acid to the desired concentration, depend-

ing upon the quality of the oil being treated.

My described reagent mixtures are equally valuable in the refining of so-called "straight-run" distillates—that is, distillates derived from crude petroleum by ordinary fractional distillation of the latter in a manner which is well understood. The process employed in the treatment of such distillates may be exactly the same in principle as that employed in the illustrations hereinbefore given; except as the quantity and composition of the reagent employed may be varied to suit the character of the distillate or other oil treated. For instance, for refining an ordinary "straight-run" kerosene distillate, for the production of illuminating oil, such distillate may be treated with anywhere from five to fifteen pounds or more per barrel of either a saturated reagent mixture, or with a mixture having the indicated character but diluted to a different ratio of free sulphuric acid,—the other steps being presumably as hereinbefore described; or the distillate, after treatment with a reagent mixture, may be washed with water,—as may also be done after treatment with alkali. The same general course may be followed in the treatment of other "straight-run" distillates.

My described reagent mixtures are of special value in the treatment of lubricating stocks, because, as is well known, in the present method of treating these stocks, using large quantities of sulphuric acid, the polymerizing losses are extremely high; whereas, by treatment with this new aromatic hydrocarbon-sulphuric acid reagent, such polymerization and sulphonation losses are entirely or largely avoided.

From a consideration of the foregoing statements it will be seen that the great advantages accruing from the use of my described reagents, in place of sulphuric acid, for the treatment of petroleum and its distillates, may be summed up as follows: Up to the present time it has been found impossible satisfactorily to remove the sulphur compounds from these "cracked" distillates by means of sulphuric acid,—so that the refined "cracked" distillate would conform to standard specifications, without incurring losses which were so high as to render such treatment commercially impracticable. On the other hand, by the use of my described reagents in which the polymerizing, oxidizing and sulphonating action of the sulphuric acid on the petroleum hydrocarbons is neutralized, modified or controlled by the admixture with such acid of an "aryl" body or "benzol homologue" such as benzene, toluene and/or xylene, as herein described, I am enabled to use, without incurring the mentioned losses, as much of such modified acid as may be required for the proper removal of the sulphur compounds in such distillate.

- Referring again to the action of my reagent mixtures upon the sulphur compounds contained in petroleum distillates or analogous oils, it would appear that during the treatment of such distillates with the reagent mixtures, as hereinbefore described, a reaction occurs between the aromatic radicle or radicles contained in the acid and such sulphur compounds,—through which either 5 a substitution or rearrangement occurs which is of such nature as to greatly modify the character of the ultimate reaction product, with apparent production of sulphur compounds having much higher boiling-points than those contained in the untreated distillates; and it may be upon the mentioned facts and relationships, and upon the properties of the resultant bodies, that the value of my described reagents, or equivalent reagents for the purpose described, will be found, in final analysis, to depend. Except for such reactions and relations, it would appear impossible to obtain the results stated above, because upon distilling 20 the untreated distillate exactly as has been described for the treated distillate, the sulphur compounds are carried over practically in their original quantity and concentration; but it should be understood that, although I now regard the mentioned aryl-bodies, or other bodies capable of undergoing various sulphonations, not only as diluents of the sulphuric acid and/or anhydride, but also as solvents, catalysts and/or reacting bodies, 25 I herein commit myself to no specific theory,—preferring to base my demands for protection merely upon an adequate exposition of the materials and methods employed.
- In one of the above specific illustrations of the use of my method of refining, I have stated that, in making the final distillation of the refined product, the addition of a small quantity of caustic potash solution to the contents of the still was made. The chief reason for this is the fact that among the sulphur compounds remaining in the oil (and some of which are formed by reactions already referred to) there are some that, although they are apparently of a neutral character under ordinary conditions, nevertheless contain acid radicles; and, when these compounds are heated to a moderate or sufficiently high temperature, in the absence of any alkali, the decomposition 30 thereof yields free acids—which may react unfavorably with desired hydrocarbons. However, if this heating takes place in the presence of a basic substance, such as potassium hydrate or sodium hydrate, the mentioned deleterious action is avoided. In other words, the presence of the basic substances during heating has the effects of still further stabilizing the sulphur compounds and insuring their retention in or by the still-bottom; but the necessity for and the proportioning of any alkali used at this point should be understood to depend not only upon the character of a crude that may have been subjected to e. g. a cracking treatment, but also upon the cracking technique—70 some cracking methods being more favorable than others to the retention of sulphur in still bottoms after use of my described reagents.
- By way of a final emphasis upon the economic importance of my invention, I may comment that, at the present time, cracking of oils is being practiced to such an extent that approximately one hundred thousand barrels of "cracked" gasoline is being produced per day within the United States. This oil sustains a loss of at least ten percent in refining, amounting to at least ten thousand barrels lost per day.75
- At an estimated value of ten cents per gallon of such lost fuel, or four dollars and twenty cents per barrel, this aggregates a daily loss of forty-two thousand dollars per day,—aside from avoidable refining costs and the avoidable depletion of natural resources. The present practice throws away the most valuable power-producing elements (high in energy and in anti-knocking qualities) that are present in the distillates derived by the cracking of oil.80
- Engineers skilled in explosive engine design and in the use of fuels in internal combustion engines are known to be seeking special hydrocarbon fuels of proper gravity (low in sulphur content and high in unsaturated hydrocarbons) for the reason that, with such fuels, a high compression engine may accomplish about double the amount of work done by the present impoverished grades of fuel, as used in the present engines; and accordingly, although, by use of my process, a saving of some ten per cent in volume (unsaturates heretofore lost in refining) can be made, this saving may, in view of the above considerations, actually be of less importance than the increase in power given by my new fuel.85
- Thus, for example, the travel radius of not only self propelled land and water devices but also that of air vehicles may be approximately doubled, or a corresponding decrease may be effected in the weight of fuel carried,—this being a most important factor in air transportation, whether in peace or war.90
- Although I have herein described complete embodiments of my invention (in the practice of which any water produced by reaction may be largely or entirely taken up by combination with SO_3 to produce H_2SO_4 ,—so that the mixture remains substantially anhydrous, and aqueous ionization of sulphuric acid may be largely or entirely prevented) it should be understood that my selection of aromatic or other hy-95100105110115120125130

- drocarbons for the indicated uses may depend not only upon reactive relationships and solubilities but upon market or other conditions.
- 5 It may be pertinent here to remark that, in a general way and within certain limits, the boiling-points of the resultant aromatic-aliphatic sulphur compounds as produced by distillation in the presence of my described 10 sulphonic-sulphuric stabilizing agent, or its equivalent, may be controlled, according as either benzene, toluene or xylene is used in the making thereof. The boiling-points of the sulphur compounds, as produced by the 15 indicated reactions, will increase in the order named,—from benzene to xylene; and it will be seen that from this point of view (and depending upon the nature of the sulphur bodies to be removed) a comparatively 20 impure benzene (containing considerable toluene and/or xylene) may actually be superior, for the purposes herein considered, to a more highly refined and expensive material. As a matter of theoretical interest, I 25 may also mention that other stabilizing agents (containing, e. g., selenic acid or other non-volatile mineral acid) might be employed in place of those described, but are not now obtainable at satisfactory prices.
- 30 Concentrated selenic acid exerts very much the same action upon cracked distillates as does sulphuric acid; and while it has not exactly the same affinity for aromatic hydrocarbons as has sulphuric acid, I find 35 that when selenic acid is treated with benzene, toluene or xylene, as described above in the case of sulphuric acid, its polymerizing action on the unsaturated hydrocarbons contained in cracked distillates is modified in 40 the same way as in the case of sulphuric acid, and that a similar reaction between the sulphur compounds contained in the distillate and the aromatic hydrocarbon-selenic acid mixture occurs, with formation of sulphur and selenium compounds of high boiling-points.
- 45 All things considered, my experience points toward a very extensive use of a reagent such as may be formed by admixing about three parts of a fuming sulphuric acid (such as may contain about twenty percent or slightly more of free SO_3) with about one part of a "commercial" or below-standard "benzene"—the various reactions which 50 promptly follow being effective to liberate enough water approximately to combine with the free SO_3 , producing additional H_2SO_4 ; but, although I have indicated that, depending upon the character of the oil treated, I 55 may add more fuming sulphuric acid to a benzol-saturated mixture so produced (in order to preserve a substantially anhydrous condition, during treatment of said oil) I may also mention that I have, in other cases 60 (as, in the treatment of a cracked distillate
- having an end point at 437° F . and containing 0.68% of sulphur) obtained entirely satisfactory results by the use of a reagent prepared by adding to two parts of a benzol-saturated mixture (obtained in the general 70 manner just described) one part of ordinary commercial sulphuric acid, containing about 95% of H_2SO_4 and about 5% of water. It is to be understood that, in the treatment of any oil of the character referred to, I employ my reagent as formed by the saturation of anhydrous sulphuric acid with an aromatic hydrocarbon, but in some instances where the oil to be treated contains certain unsaturates or refractory sulphur compounds 80 which resist chemical treatment, I find that by adding to my reagent an additional quantity of sulphuric acid, as hereinabove indicated, that a more intense action is obtained, resulting in the desired action on such resistant compounds. By using this added sulphuric acid, I am enabled to perfectly control the "acid treatment" of the oil which is a feature of major importance in the refining 85 industry.
- 90 In the above illustrations of the use of my reagent and process, nothing has been said as to the preliminary treatment of the crude distillates, as received from the cracking-units, for the removal of HS sulphur compounds contained in such crude distillates, (as by washing with caustic soda or sodium plumbite solution, etc.) the occasion for such preliminary treatment being understood by all refiners; and no special temperatures at 95 which the treatment is applied have been given. As a general rule, the oil may be at the ordinary temperature of the atmosphere; though in the case of some distillates containing very high percentages of highly 100 unsaturated hydrocarbons, such as those derived from the oil shales, it may be found advantageous to apply the treatment at comparatively low temperatures. As is the case in practically all chemical reactions of this 105 description, an increase in the temperature increases the intensity of the reaction or reactions; but it is common knowledge that the refiner must be governed by the character of the oil under treatment and by his experiences therewith.
- 110 Finally it should be understood that various features of this invention may be independently employed; and also that numerous modifications of my invention might easily be devised, by those workers skilled in the arts to which this case relates, without involving the slightest departure from the spirit and scope of this invention, as the same is indicated above and in the following 115 claims.
- 115 I claim as my invention:
- 120 1. The method of preparing a reagent for treating mineral oils to reduce the sulphur content thereof, which comprises saturating 125

fuming sulphuric acid with an aromatic hydrocarbon.

2. The method of preparing a reagent for treating mineral oils to reduce the sulphur content thereof, which comprises saturating fuming sulphuric acid with an aromatic hydrocarbon of the benzene series.

3. A method of reducing the sulphur content of mineral oils which comprises: treating the same with reagent mixture which results from saturating fuming sulphuric acid with an aromatic hydrocarbon.

4. A method of reducing the sulphur content of mineral oils which comprises: treating the same with reagent mixture which results from saturating fuming sulphuric acid with an aromatic hydrocarbon, while maintaining the mixture within atmospheric temperatures.

5. A method of reducing the sulphur content of mineral oils which comprises: treating the same with a reagent mixture which results from saturating fuming sulphuric acid with a hydrocarbon of the benzol series.

6. A method of reducing the sulphur content of mineral oils which comprises: treating the same with reagent mixture which results from saturating fuming sulphuric acid with an aromatic hydrocarbon, said sulphuric acid containing SO_3 in quantity sufficient to combine with water formed by reactions between said acid and said hydrocarbon.

7. A method of reducing the sulphur content of mineral oils which comprises: treating the same with a reagent mixture comprising fuming sulphuric acid saturated with an aromatic hydrocarbon and thereafter separating a sulphur-containing sludge from the oil.

8. A method of reducing the sulphur content of mineral oils which comprises: treating the same with a reagent comprising fuming sulphuric acid saturated with an aromatic hydrocarbon, thereafter separating a sulphur-containing sludge from the oil and redistilling the oil.

9. A method of reducing the sulphur content of mineral oils which comprises: treating the same with a reagent comprising fuming sulphuric acid saturated with an aromatic hydrocarbon, thereafter separating a sulphur-containing sludge from the oil and redistilling the oil up to any certain end point.

10. A method of reducing the sulphur content of mineral oils without avoidable polymerizing and oxidizing effects which comprises: treating the oil with a reagent comprising fuming sulphuric acid, saturated with an aromatic hydrocarbon while maintaining the mixture within atmospheric temperatures; treating the oil with this reagent to form a sludge; separating the sludge from

the oil and subjecting the resultant oil to distillation.

11. A method of reducing the sulphur content of mineral oils without avoidable polymerizing and oxidizing effects which comprises: treating the oil with a reagent comprising fuming sulphuric acid, saturated with an aromatic hydrocarbon while maintaining the mixture within atmospheric temperatures; treating the oil with this reagent to form a sludge; separating the sludge from the oil and subjecting the resultant oil to distillation.

12. A method of treating mineral oils containing sulphur bodies and unsaturates, without avoidable polymerizing and oxidizing effects, which comprises: subjecting fuming sulphuric acid to a preliminary treatment with an aromatic hydrocarbon which reduces its tendency toward polymerizing and oxidizing effect on the oil without destroying its action upon sulphur bodies, and then admixing the so-treated sulphuric acid with said oil.

13. A method of treating mineral oils containing sulphur bodies and unsaturates, without avoidable polymerizing and oxidizing effects, which comprises subjecting fuming sulphuric acid to a preliminary treatment with an aromatic hydrocarbon which increases its tendency to elevate the boiling-point of said sulphur bodies; then reacting upon the oil with the so-treated acid; separating a resultant sludge from the oil, containing some sulphur bodies; neutralizing residual acid in the oil; separating the products of neutralization from the oil; and subjecting the separated oil to a distillation in the presence of an alkali.

14. A method of reducing the sulphur content of mineral oils which comprises: treating same with a reagent mixture which results from saturating fuming sulphuric acid with an aromatic hydrocarbon to form a mixture while maintaining the mixture within atmospheric temperatures, and then adding sulphuric acid to the resultant product.

15. A non-sulphonating, non-polymerizing, non-oxidizing reagent for treating petroleum oils comprising a solution consisting of fuming sulphuric acid saturated with an aromatic hydrocarbon.

16. A non-sulphonating, non-polymerizing, non-oxidizing reagent for treating petroleum oils consisting of a solution composed of fuming sulphuric acid saturated with an aromatic hydrocarbon to which solution a further addition of sulphuric acid has been made.

17. The method of treating mineral oils containing sulphur bodies and unsaturates without avoidable polymerizing and oxidizing effects, which comprises subjecting said

oils to a treatment with a reagent comprising a solution composed of fuming sulphuric acid, saturated with an aromatic hydrocarbon, separating the sludge, resulting from said treated oil, from the oil, neutralizing the separated oil with an alkali, separating the products of neutralization from the oil, adding a still base and an alkali to the so treated neutralized oil and subjecting the mixture of still base, alkali and treated oil to a distillation.

18. The method of treating mineral oils containing sulphur bodies and unsaturates without avoidable polymerizing and oxidizing effects, which comprises subjecting said oils to a treatment with a reagent consisting

of a solution composed of fuming sulphuric acid, saturated with an aromatic hydrocarbon, to which addition of sulphuric acid has been made, separating the sludge, resulting from said treated oil, from the oil, neutralizing residual acid in the separated oil with an alkali, separating the products of neutralization from the oil, adding a still base and an alkali to the so treated neutralized oil and subjecting the mixture of still base, alkali and treated oil to a distillation.

In testimony whereof, I have hereunto set my hand at Los Angeles, California, this 20th day of December, 1926.

FRANK C. AXTELL
